UNITED STATES PATENT OFFICE.

GEORGE M. BAYNE, OF HAMILTON, ONTARIO, CANADA, ASSIGNOR TO WESTINGHOUSE ELECTRIC & MANUFACTURING COMPANY, A CORPORATION OF PENNSYLVANIA.

WATER HEATER.

Application filed October 23, 1923. Serial No. 670,347.

To all whom it may concern:

Be it known that I, GEORGE M. BAYNE, a subject of the King of Great Britain, and a resident of Hamilton, in the Province of Ontario, Canada, have invented a new and useful Improvement in Water Heaters, of which the following is a specification.

My invention relates to electrically heated devices and particularly to electric fluid heaters.

One object of my invention is to provide a relatively simple, inexpensive, and easily constructed fluid heater.

Another object of my invention is to provide a fluid heater having an electric heating element that may be easily and quickly removed therefrom.

Another object of my invention is to provide a fluid heater that shall permit of its being constructed in any desired length with but few changes of its component parts.

In practicing my invention, I provide an outer casing that is built up of standard pipe or conduit parts and an inner casing substantially co-extensive therewith, the two casings being operatively connected at their lower ends only and having an annular water chamber therein. An electric heating element is located in the upper part only of the inner casing within which it is supported by a combined terminal lead and supporting member.

A plurality of terminal members are mounted on a terminal bridge that is supported on the lower end of the outer casing. A terminal box is secured to the lower end of the outer casing, and it has mounted on its outer surface a suitable control switch.

In the single sheet of drawings,

Figure 1 is a view, in vertical longitudinal section, of a fluid heater embodying my invention,

Fig. 2 is a view, in side elevation, of a unitary heating element and terminal structure.

Fig. 3 is a view, in side elevation, of a refractory resistor supporting section,

Fig. 4 is a top plan view of a refractory spacer and

Fig. 5 is a schematic view in side elevation, of a heating system comprising the device embodying my invention.

An outer casing for a heater comprises a standard reducing pipe coupling 11 that is mounted on the upper end of a length of

standard pipe 12, to the lower end of which there is secured a standard reducing pipe 13. A terminal supporting member 14, of substantially tubular form, has screw-threaded engagement with the lower end of the member 13 and is provided with an inwardly extending screw-threaded flange portion 15.

An inner casing 16 comprises a seamless metal tube of relatively thin material, closed at its upper end and open at its lower end which is provided with screw threads co-operating with the screw-threaded flange portion 15 to permit of close operative engagement between the inner casing member 16 and the terminal head 14. The inner dimensions of the members 12 and 14 and the outer diameter of the inner casing 16 are such as to provide an annular water chamber 17 between the two members that may be of any suitable or desired radial thickness.

A heating element 18 comprises a plurality of tubular members 19, of a refractory electric-insulating material, that are respectively provided with relatively wide screw threads on their outer surface within which a suitable resistor member 21 may be located. The members 19 are provided with recesses 22 at one end and with corresponding projections 23 at their other end in order that the adjacent members 19 may interlock with each other and preventing turning movement of one member relatively to an adjacent member. The screw threads are of double pitch in order that two sections of the resistor member 21 may be wound simultaneously from one end of the assembled members 19 toward the other end whereby both ends of the resistor member 21 are brought out at one end of the heating unit.

At the upper end, the resistor member 21 is electrically connected to the upper end of a clamping stud 24 to which it is secured by a plurality of co-operating nuts 25. The stud 24 is maintained co-axially with the members 19 by means of a spacer 26 of suitable refractory material that is held in its proper operative position relatively to the stud 24 by a plurality of nuts 27. A spacer 26 is mounted on the lower end of the stud 24 and held thereon by co-operating nuts 27, the two spacers being of course so located relatively to each other and to the plurality

of abutting and interlocked sections 19 as to be located closely adjacent to and within the respective outer ends of the end members 19.

5 A combined terminal lead and heating-unit-supporting member 28 comprising a relatively narrow metal bar, of substantially L-shape, has its upper end secured to the lower end of the stud 24 by a nut 27 clamp-
10 ing the end of the member 28 against the other nut 27 provided for holding the spacer 26. The lower end of the member 28 is secured to a terminal member 29 comprising a screw-threaded stud and a plurality of
15 nuts 31 that are insulatedly mounted on a terminal bridge 32 comprising a metal bar bent to substantially U-shape. The lower ends of the resistor member 21 are electrically connected to suitable terminal members
20 33 and 34 mounted on the terminal bridge 32, by means of terminal leads 35 and 36. The terminal members 33 and 34 are here illustrated as comprising a bolt or stud and a plurality of co-operating nuts mounted
25 thereon, and operative to secure the stud or bolt on the terminal bridge and also to hold the end of the terminal leads thereon. However, any suitable or desired type of terminal member may be employed.
30 A terminal box 37 is secured to the bottom end of the terminal head 14 by means of a plurality of machine screws 38. The terminal box 37 is provided with a removable bottom plate 39 to permit of easy access to the terminal leads and terminal members. The terminal bridge 32 has its two ends operatively secured against depending lugs 41 integral with the bottom portion of
35 the terminal member 14, machine screws 42 serving to clamp the bridge 32 against the lugs 41.

40 A suitable control switch 43 is secured against the outer surface of the terminal box 37 and its terminals are connected to the terminal members 31, 33 and 34 by a plurality of conducting leads 44. Supply circuit conductors 45 connect proper terminals of the control switch 43 to a suitable source of electric energy (not shown).

50 Fig. 5 of the drawing illustrates schematically the connections of my water heater to a tank 46. The other connections for the supply and the removal of the water are those ordinarily used and hence not further illustrated or described.

55 It may be noted that the water enters the heater through an opening 47 in the pipe T 13 and leaves the heater at the top thereof through the member 11. The annular space 17 extends well below the heating element 18 that is of such length that it is located in the upper portion only of the inner casing 16, its lower end being substantially opposite the inlet opening 47. This construction provides a water pocket in the terminal

member 14 forming a thermal lock in the annular space 17 at the lower end thereof and is very effective in keeping the temperature of the terminals and of the terminal leads at a relatively low value.

70 The heating unit 18 may be easily and quickly removed from its normal operative position within the inner casing 16 after having removed the bottom plate 39 from the terminal box 37. By removing the screws 38, the switch box may be moved downwardly, the leads 44 being made long enough to permit of this, after which the leads 44 may be disconnected from the terminals 31, 33 and 34. The heating unit 18, together with the terminal leads and the terminal bridge may then be removed as a unit downwardly from the heater by removing the screws 42, thereby permitting repairs to be made to the heating unit and the heater to be reassembled quickly and easily.

80 It is possible to vary the length of the entire heater by varying the length of the member 12 and by employing a suitable number of resistor-supporting members 19, it being understood of course that if a heating unit of greater capacity is desired, it is necessary to use a resistor member 21 of heavier wire to permit a larger current to traverse the same when in actual operation.

85 By using a single resistor 21 that is wound in the double pitch screw threads and by connecting the middle of its length to the stud 24 at the top thereof, as hereinbefore described, it is possible to provide a three-heat control of the resistor, in which case, the control switch 43 should be of a corresponding type of construction.

90 Various modifications and changes may be made herein without departing from the spirit and scope of the invention, and I desire, therefore, that only such limitations shall be placed thereon as are imposed by the prior art or are set forth in the appended claims.

95 I claim as my invention:

100 1. In an electric water heater, in combination, an elongated inner casing having a closed upper end, an electric heating element in the upper part only of said inner casing, terminal leads connected thereto and extending beyond the lower end of said inner casing, and an elongated outer casing enclosing said inner casing, operatively connected thereto at its lower end only, and providing an annular water chamber, said outer casing having an outlet at the top thereof and an inlet intermediate its ends, that portion of the water chamber below the inlet constituting a thermal lock for the terminal leads.

105 2. In an electric water heater, in combination, an elongated inner casing, an elongated outer casing enclosing said inner casing, said

casings being connected at their lower ends only and having an annular water chamber therebetween, an electric heating element in the upper end only of said inner casing 5 and a combined terminal and heat-element supporting member directly secured to and operatively supported from the lower end of said outer casing.

3. In an electric water heater, in combination, an elongated inner casing, an elongated outer casing enclosing said inner casing, said casings being connected at their lower ends only and having an annular water chamber therebetween, an electric 15 heating element in the upper end only of said inner casing, terminal leads depending from said heating element, a terminal bridge secured to and supported by said outer casing and terminal members mounted thereon, 20 said heating element, terminal leads, terminal bridge and terminal members being removable as a unit from said inner casing.

4. In an electric water heater, in combination, a pair of substantially coextensive and 25 coaxial casings having an annular water chamber therebetween, a heating unit in said inner chamber, a terminal bridge mounted directly on the outer casing at the lower end thereof, and a combined terminal

lead and heating-unit-supporting member 30 supported by said terminal bridge.

5. In an electric water heater, in combination, a pair of substantially coextensive and coaxial casings having an annular water chamber therebetween, a heating unit, comprising a plurality of coaxial, abutting, 35 grooved tubular refractory members and a resistor member wound in said groove, and a combined terminal lead and heating-unit-supporting member associated therewith. 40

6. In an electric water heater, in combination, a pair of substantially coextensive and coaxial casings having an annular water chamber therebetween, a heating unit, comprising a plurality of interfitting refractory 45 members having a plurality of grooves on the outer surface thereof, and a resistor member in said grooves, a heating-unit-supporting member electrically connected to said resistor member at the top of said unit, and a terminal bridge having secured thereto one end of said heating-unit-supporting member. 50

In testimony whereof, I have hereunto subscribed my name this 20th day of September 1923. 55

GEORGE M. BAYNE.
